UNITED STATES PATENT OFFICE.

NEIL T. ALBRIGHT, OF KOKOMO, INDIANA.

PROTECTING PLATE FOR MIRROR BACKS.

Application filed March 5, 1923. Serial No. 622,917.

To all whom it may concern:

Be it known that I, NEIL T. ALBRIGHT, a citizen of the United States, and a resident of Kokomo, county of Howard, and State 5 of Indiana, have invented a certain new and useful Protecting Plate for Mirror Backs; and I do hereby declare that the following is a full, clear, and exact description thereof, reference being had to the accompanying 10 drawings, in which like numerals refer to like parts.

This invention relates to a protecting plate for the back of mirrors, and particularly so-called rear view mirrors adapted 15 to be clamped to a vehicle.

In this type of mirror there is no frame or backing as is the case in a door or wall mirror, thus leaving in some instances the paint used on the back of the mirror unprotected. The paint so used is more or less brittle so that it is apt to be nicked off and the mirror ruined if it comes in contact with a hard or sharp article, or be affected by the weather so as to peel or blister. Efforts to 25 provide a paint which would not nick off, scratch, or be affected by the weather so as to show through the mirror, having failed, it has been necessary to provide a protection for the paint. Wherein effort has been made to glue cel- 30 luloid or similar material over the back of the mirror, the same difficulty has been had, in addition to the difficulty of securing the edges of the material to the edges of the mirror.

40 It is, therefore, the object of this invention to provide a backing formed of celluloid, pyralin, aluminum or similar material to be held in position thereon by the ordinary clamping bracket, or other securing means, in such manner that the free ends or edges of the backing will be held tightly against the back surface of the mirror while the greater portion thereof will be spaced therefrom. This arrangement gives a neat 45 appearance to the back of the mirror which may be colored in any suitable manner desired and eliminates the necessity of securing the material to the edges of the glass and permits ready expansion and contraction, 50 without affecting the paint.

The full nature of this invention will be

understood from the accompanying drawings and the following description and claims.

In the drawings Fig. 1 is a plan view of 60 the protecting plate. Fig. 2 is an end elevation thereof mounted upon the mirror. Fig. 3 is a section taken on the line 3—3 of Fig. 1 showing the plate mounted upon the mirror. Fig. 4 is a section taken on the line 65 4—4 of Fig. 1. Fig. 5 is a plan view of the clamping means. Fig. 6 is a section taken on the line 6—6 of Fig. 5 showing the clamping means secured to the mirror and the support therefor.

70 In the drawings there is shown a protecting plate for the back of a mirror adapted to be clamped thereon formed of celluloid or similar material and of the same general size and shape as the mirror to which it is to be clamped. In this case a protecting plate 9 is applied to the mirror, oblong in shape, and is of such size as to extend over the entire back thereof. The celluloid plate is formed dish-shaped with an outer flanged edge 10 extending about its periphery, from which there arises an inclined sloping or bevel-like border 11. From the end borders 11 there is a sloping portion 12 sloping upwardly toward the center and narrowing to a longitudinal rib 13. Similarly, from the side borders 11 there is an upwardly sloping portion 14 extending from each side of the plate toward the center and meeting with the portions 12 to form the 80 ridges 15, which converge from each corner to the central longitudinal rib 13. The portions 14 are depressed on each side of the rib 13 to conform to the shape of the clamp to be used, as shown by the flat portions 16. 85 This formation of the plate gives an inverted dish-shape so that the entire inner portion thereof, with the exception of the flange 10, is spaced from the surface of the 90 mirror against which it is clamped.

100 The protecting plate is clamped upon the back of the mirror 20, by means of the clamping plates 21 having a pair of clamping ears 22 on each side thereof which grip the bevel sides of the mirror, said plates having rearwardly extending adjacent ears 23 which are secured together by the bolt 24 so that as said bolt is tightened, the ears 22 are rigidly clamped against the edges 105 of the mirror. The ears 23 are provided 110 with receiving sockets for the universal ball joint 25 which is mounted on a plate 26

adapted to be secured to the mirror support.

It will be noted that the plates 21 have the same general outline as the receiving portions 16 of the protecting plate so as to fit snugly therein, and that the rib 13 of the plate extends upwardly between the ears 23 of the clamping plates. By reason of the rib 13, sloping portions 12 and 14 with their adjacent ridges 15, and the bevel border 11, the pressure exerted by the clamping plates 21 when applied to the portion 16 forces the same downwardly toward the back of the mirror and thereby the edges of the protecting plate are pressed against the back of the mirror about the periphery thereof, including the ends and corners thereof.

The plate will thus be rigidly secured to the back of the mirror so that the outer edges and corners will be firmly held in place and still permit the same to freely expand and contract.

The invention claimed is:

1. The combination with a mirror having a treated back for covering the silver thereon, of means for covering and protecting said back comprising a protecting plate, means for clamping said plate upon the back of the mirror, and a plurality of ridges formed integral with and as a part of said plate for transmitting the clamping pressure applied at the center thereof to the outer end and side edges for holding the outer edges thereof firmly against the adjacent surface of the mirror back.

2. The combination with a mirror having a treated back for covering the silver there-

on, of means for protecting said back comprising a protecting plate, means for clamping said plate upon the back of the mirror, and a central longitudinal rib formed integral with and as a part of said plate and sloping toward the ends thereof for transmitting the pressure applied at the center to the ends for holding the outer edges thereof firmly against the adjacent surface of the mirror back.

3. The combination with a mirror having a treated back for covering the silver thereon, of means for protecting said back, comprising a protecting plate dished from the outer edges to the center, and having a plurality of ribs radiating from the center thereof, and a clamp for engaging and forcing the body of said plate toward the mirror back so that the edges only thereof will be held firmly in contact therewith.

4. The combination with a mirror having a treated back for covering the silver thereon, of means for protecting said back, comprising a protecting plate having the surrounding edge adapted to engage the back of the mirror, said plate being dished toward the center so as to be spaced therefrom, a rib formed in said plate, a ridge extending from the center outwardly, and means for forcing the body portion of the plate toward the mirror for forcibly holding only the outer edge of said plate in contact therewith.

In witness whereof, I have hereunto affixed my signature.

NEIL T. ALBRIGHT.
